(57) **CLAIM**

The ornamental design for a mobile X-ray device comprising integrated flat-panel detector, as shown and described.

DESCRIPTION

FIG. 1 is a front elevation view of a mobile X-ray device comprising integral flat-panel detector showing our new design;

FIG. 2 is a rear elevation view thereof;

FIG. 3 is a top plan view thereof;

FIG. 4 is a right side elevation view thereof;

FIG. 5 is a left side elevation view thereof;

FIG. 6 is a bottom plan view thereof;

FIG. 7 is a top, rear, and right side perspective view thereof; and,

FIG. 8 is a bottom, front, and left side perspective view thereof.

The broken lines in the drawings illustrate portions of the mobile X-ray device comprising integral flat-panel detector that form no part of the claimed design.
